Henry Fernhume, of New York, N.Y.
Letters Patent No. 1575, dated May 6, 1862.

The schedule referred to in these Letters Patent and making part of the same.

To all whom it may concern:

Be it known that I, Henry Fernhume, of the City, County and State of New York, have invented or produced a new and original Design for a Clock Case; and I do hereby declare that the following is a full, clear and exact description of the same, reference being had to the accompanying drawings, making a part of this specification, in which -

Figure 1. is a front or face view of a clock case constructed according to my design.

Figure 2. a transverse central section of the same.

Similar letters of reference indicate corresponding parts in the two Figures.

This design consists of an octagonal case having its face side provided with a moulding, the outer part of which is a narrow torus a, at the inner side of which there is a wide scotia b, having a torus c, at its inner edge and a quirked scotia d, at the inner side of the latter. Within the scotia d, there is a flat or plane surface e.

This moulding as well as the plane surface e, extends all around the clock case forming its face or front side, the octagonal form of the case being preserved or well defined in the moulding by having radial joints or lines of junction f, as shown clearly in Figure 1.

The moulding projects considerably out beyond the plane surface e, as shown in Figure 2, so as to give the front of the clock a bold and frame-like appearance.

The inner edge of the plane surface e, of the case is also of octagonal form corresponding to the outer edge of the case, as shown clearly in Figure 1.

The width of the moulding and plane surface e, at the joints f, is equal to about one quarter of the diameter of the case, and

Des. 1575

the space or opening q , at the centre of the case, is consequently equal in diameter to one half the diameter of the case.

Having thus described my invention, what I claim as new and desire to secure by Letters Patent, is

The general configuration of the parts herein shown and described, to form a new and original Design for a Clock Case.
